UNITED STATES PATENT OFFICE.

HERMAN H. CLAUSSEN, OF SAN ANTONIO, TEXAS.

LOCK MECHANISM.

Application filed April 11, 1922. Serial No. 551,456.

To all whom it may concern:

Be it known that I, HERMAN H. CLAUSSEN, a citizen of the United States, residing at San Antonio, in the county of Bexar and State of Texas, have invented certain new and useful Improvements in Lock Mechanism, of which the following is a specification.

This invention relates to automatic auxiliary safety locks for employment upon the doors of vaults and safes and has as its general object to provide means for preventing withdrawal of the locking bolts, constituting a part of the usual lock mechanism, even should the combination of the mechanism be blown out or otherwise destroyed. The method of procedure followed by a safe blower is usually to destroy the combination lock by explosive or some other destructive agent thereby exposing parts of the lock mechanism which may then be readily manipulated to retract the bolts. Therefore the present invention contemplates the provision of means which while normally inactive will be automatically rendered active to constitute an auxiliary lock in the event the combination lock is destroyed or displaced, and rendering it impossible to retract the bolts of the lock mechanism through manipulation of any of the elements of such mechanism which might under the stated conditions be exposed.

Another object of the invention is to provide a springless auxiliary lock mechanism such as that above referred to which, while it cannot possibly be actuated by operating through the opening uncovered when the combination lock is destroyed, may nevertheless be rendered inactive in a more or less convenient manner by one possessing the required knowledge, and thus permit the vault or safe door to be opened after an attempt has been made to gain access to the vault or safe.

In the accompanying drawings:

Figure 1 is a sectional perspective view illustrating the mechanism embodying the invention and so much of a vault door and the automatic lock mechanism as is necessary for an understanding of the invention;

Figure 2 is a horizontal sectional view through the mechanism of the invention; and

Figure 3 is a vertical sectional view taken substantially on the line 3—3 of Figure 2 looking in the direction indicated by the ar-

rows and illustrating the manner in which the auxiliary lock mechanism may intentionally be rendered inactive after it has been released through destruction of the combination lock.

In the drawings the numeral 1 indicates in general a vault or safe door which is provided upon its inner face with the usual flange 2 through which the bolt rods 3 of the usual lock mechanism are slidably projected to engage in sockets in the frame of the door opening. Numeral 4 indicates the usual connecting frame bar which is secured to associated ones of the bolt rods 3, and the numeral 5 indicates the usual combination devices of the lock mechanism. All of these parts may be of the ordinary or any preferred construction, and as previously stated, if the combination lock 5 is destroyed or displaced, some part of the lock mechanism will be exposed in a manner to permit of its manipulation to retract the bolt rods, means being provided by the present invention however for preventing this being done as will now be explained.

The auxiliary lock mechanism of the present invention is indicated in general by the numeral 6 and comprises a base plate 7 which is fixed in any suitable manner and at any convenient point of location upon the inner face of the door 1. Bearing members 8 are mounted upon this plate and rotatably support a shaft 9 which extends at right angles to the length of the adjacent connecting bar 4. At its end adjacent said bar 4, the shaft 9 is provided with a substantially right angularly extending locking head 10 which is located relatively close to the inner vertical edge of the said connecting bar 4. The shaft 9 is slidably adjustable as well as rotatable in the bearings 8, and an adjusting and abutment screw 11 is threaded through a boss 12 upon the plate 7 and is adapted to bear against or constitute an abutment for that end of the shaft which is opposite the end carrying the locking head 10. An adjustable abutment plate 13 is slidably disposed against the face of the plate 7 and secured in positions of adjustment by means of a set screw 14 engaged through a slot 15 therein and into the plate 7. The said plate 13 is provided at one end with an outstanding lip 16 against which the end of the shaft 9 which carries the locking head 10 may abut as shown in Figures 1 and 2 of the

drawings. In the use of the mechanism it will be customary to adjust the plate 13 and secure the same in such position of adjustment that when the last mentioned end of the shaft 9 is in engagement against the lip 16, and the connecting bar 4 for the bolt rods 3 is in the position which it will assume when the bolt rods are projected to locking position, the edge of connecting bar 4 next adjacent the said end of the shaft will occupy a plane but slightly spaced from the plane of the adjacent side of the locking head 10, and after this adjustment has been obtained, the screw 11 is rotated until its end will bear lightly against or be located very close to the adjacent end of the shaft 9. By reference to Figure 2 it will be observed that the connecting bar 4 is somewhat spaced from the plane of the inner face of the door 1, and it will be evident that when the shaft 9 is rotated to such position that the head 10 will project vertically, the said head will be out of the path of movement of the connecting bar 4 in the retractive movement of said bar. On the other hand if the shaft 9 is rotated so as to lower or swing the head downwardly to substantially the horizontal position shown in dotted lines in Figures 1 and 3 of the drawings, this head will be directly in the path of the connecting bar 4 and retraction of the bar will be prevented.

In order that the shaft 9 may be normally held in the first mentioned position of adjustment, the shaft is provided at some suitable point in its length with an outwardly projecting pivot lug 17 to which is pivotally connected a weight block 18, the block being freely suspended from the pivot which is indicated by the numeral 19. A wire or small rod 20 is connected at its upper end in any suitable manner as at 21 to the lower end of the suspended weight block 18, and at its lower end as at 22 to the combination mechanism 5, and this element constitutes means, by reason of a proper proportioning of its length, for normally supporting the weight block 18 in the elevated position shown in full lines in Figure 1. When the weight block occupies this position the shaft 9 will be so positioned that the locking head 10 will extend vertically and be sustained out of the path of movement of the connecting bar 4, and so long as the ordinary lock mechanism is manipulated in a proper manner, the auxiliary lock mechanism will be inactive. However if an attempt is made to gain access to the vault or safe by destroying or displacing the combination lock 5, support will be withdrawn from the weight block 18 thus permitting this block to fall by gravity, and by reason of its weight, its downward movement will result in a rotation of the shaft 9 to lower the locking head 10 to the dotted line position shown in the

said Figure 1 in which position it will be in the path of movement of the connecting bar 4. Thus when the combination lock is destroyed or displaced, the auxiliary lock mechanism will be immediately rendered active so as to effectually prevent retraction of the bolts 3 by an unauthorized person. However in order that it will not be necessary to further mutilate the door of the safe or vault in order to gain access to the lock mechanism and make the necessary repairs, the owner of the safe will at the time of purchase be apprised of the location of the weight block 18 with relation to one or more edges of the door 1 and may, for the purpose stated, bore through the door at a point opposite the point of location of the said weight block, and by inserting any tool or other implement suitable for the purpose such for example as the drill bit employed in boring the opening, may, as illustrated in Figure 3, force the weight block 18 in an inward and upward direction and against the wall of a casing 23 which is secured upon the inner face of the door 1 and extends over the auxiliary lock mechanism. When the weight block is displaced in this manner, the shaft 9 will be rotated to a position to cause the locking head 10 to extend vertically in its normal position and clear of the connecting bar 4, and while the parts are held in this position the ordinary lock mechanism may be manipulated to retract the bolts.

Having thus described the invention, what is claimed as new is:

1. The combination with a main lock mechanism including a shiftable bolt member and a combination device subject to displacement by violence, of an auxiliary lock mechanism comprising a freely rotatable shaft, a locking head extending therefrom and angularly movable, in the rotation of the shaft, between a position out of the path of movement of the bolt member and a position in the path of movement of said member, and means tending to overbalance the shaft and rotate the same to move the locking head to locking position and including a sustaining element connected with the combination device, the said overbalancing means comprising a weight suspended beyond the shaft, and the said sustaining element comprising a relatively rigid member connected at one end to the said weight and at its other end to the said combination device.

2. The combination with main lock mechanism including a shiftable bolt-member and a combination device subject to displacement by violence, of an auxiliary lock mechanism comprising a bearing, a rotatable shaft freely shiftable adjustable in the bearing, a locking head extending from the shaft and angularly movable, in the rotation of the shaft, to a position in and out of the

- path of movement of the bolt member, means tending to overbalance the shaft and rotate the same to move the locking head to locking position, means connected with the combination device normally restraining the overbalancing means, and adjustable abutments for the ends of the shaft whereby the locking head may be adjusted with relation to the bolt member.
- 10 3. The combination with main lock mechanism including a shiftable bolt member and a combination device subject to displacement by violence, of an auxiliary lock mechanism comprising a bearing, a shaft freely 15 rotatable and freely shiftably adjustable longitudinally in the bearing, a locking head extending from the shaft and angularly movable with the shaft to a position out of the path of movement of the bolt member
- and to position in the path of movement of the said member, an adjustable abutment for one end of the shaft, an abutment screw for the other end of the shaft adjustable to maintain the shaft in engagement with the first-mentioned abutment, an arm extending laterally from the shaft in the normal position of the shaft and in the inactive position of the head thereon, a weight block pivotally suspended from the said arm and constituting means tending to over-balance the shaft 20 and rotate the same to move the head to active position, and a sustaining element comprising a relatively rigid rod connected at its upper end to the weight and at its lower end to the combination device. 25
